FOLDING LEG FIXTURE

August P. Jurgensen, New York, N. Y., assignor,
by mesne assignments, to Rooney Metal Products Corporation, Hoboken, N. J., a corporation of New Jersey

Application March 9, 1945, Serial No. 581,778

6 Claims. (CL 311—99)

1

This invention relates to folding legs, which are adapted to be folded from operative extended positions to inoperative folded positions on such items as card tables, collapsible chairs, ironing boards, outdoor furniture and such other articles in which folding legs are preferable to solidly fastened legs.

The principal object of this invention is to provide a folding leg with a coating or changeable fulcrum around which the leg swings from an operative to an inoperative position.

Another object is to provide an extremely sturdy and inflexible fixture fastened to a folding leg, which will be easily and simply operated and which will effectively snap into locked engagement either in a folded position or an extended position.

Still another object is to provide a folding joint so strong that it will not be necessary to use diagonal braces to rigidify the legs.

Other objects and advantages of this invention will be pointed out in the following specification and accompanying drawings in which I have illustrated my invention in its application to a folding table. In the drawings:

Fig. 1 is a sectional view taken on the line 1—1 of Fig. 3 and looking in the direction of the arrows.

Fig. 2 is a view similar to Fig. 1 showing the folding leg in a different position.

Fig. 3 is a cross-section on the line 3—3 of Fig. 1 and looking in the direction of the arrows.

Fig. 4 is a view looking from bottom to top at Fig. 3.

Fig. 5 is a cross-section on the line 5—5 of Fig. 1 and looking in the direction of the arrows.

Fig. 6 is a cross-section on the line 6—6 of Fig. 1 and looking in the direction of the arrows.

Fig. 7 is a plan view showing an application of my invention to a metallic table in which my folding structure may be welded to the table or fastened in some other suitable way.

Fig. 8 is a section on the line 8—8 of Fig. 7 and looking in the direction of the arrows.

Fig. 9 is a section on the line 9—9 of Fig. 8 and looking in the direction of the arrows.

Fig. 10 is a detail on the line 10—10 and looking in the direction of the arrows.

Referring now to the drawings, my improved folding leg construction includes a stationary plate 15 fastened to the inside of the apron 16 of a table. Plate 17 is fastened to a leg 18 and swings with said leg. 19 is a spring, adapted to hold plate 17 in a locked position with plate 15. Referring more particularly to Fig. 1, in which

the leg 18 is shown in its operative extended position, the plate 15 has four pressed up portions 20 (also see Fig. 5) which are secured firmly against the apron 16 by means of screws 21. The reference character 22 indicates a restricted space in which the spring 19 is placed and free to operate. Stamped out portions 23—24 (also see Fig. 3) on the plate 17 engage and overlap notches 25—26 on plate 15 and are held in a locked, upward position due to pressure of spring 19 by means of hook 19' which goes through a hole in plate 17.

When the leg 18 is to be swung from its extended position shown in Fig. 1 to its folded position shown in Fig. 2, the leg 18 is pulled down in the direction of arrow 27, then swung in the direction of arrow 28 and the leg snaps into notches 29—30 in a locked position because of spring 19. When the leg 18 is to be moved from its folded to its extended position the operation just described is reversed. The leg 18 shown in dotted lines in Fig. 2 is an intermediate position.

The plate 15 comprises a fixed anchor member adapted to be fastened to a frame portion of a table or the like and the leg plate 17 comprises a revolvable member movable thereon and adapted to be fastened to a folding leg. These plates 15 and 17 are each substantially flat and when connected together form a thin fixture to permit insertion between narrowly-spaced adjacent side surfaces of a vertically disposed rim member and the leg. Said plates 15 and 17 have flat sliding-contact faces and, when the plates are initially slid longitudinally or linearly relatively to each other, the protruding stamped out portions or locking tongues 23—24 of the plate 17, which are raised sufficiently above said sliding-contact face of the said plate 17, will extend over the edges of the locking notches 26—30 and 25—29 in the plate 15 and over the edges of track portions 34 and 34^a between such locking notches to produce an overlapping interengagement therewith which is thereafter maintained while the plates are mounted in operative position. The leg plate 17 is urged linearly by the spring 19 in an upward direction toward said notches and tracks and parallel with the axis of the leg, and consequently the revolvable leg plate will, at all times during movement, be held in interengagement with the stationary table-plate while the flat faces of said plates will be maintained in loosely contacting relationship to permit both linear and arcuate sliding movement of the leg plate over said fixed plate. Thus, the flat outer face of the fixed plate 15 serves as a

base on which the flat outer surface of the revolvable leg-plate 17, in its movement from folded to extended positions and vice versa, rubs and rides through a quadrant arc of a circle. The locking notches 26 and 30 are formed within the borders of the plate 15 and are internal notches adapted to produce a primary locking of the plates while the locking notches 25 and 29 are external notches formed in the outer edge of said plate in alignment with said internal notches. As illustrated, an internal substantially circular aperture 33 is provided within the borders of the stationary plate 15 and the locking notches 26 and 30 are formed at quadrantial positions in the upper edges of said aperture and are connected by a track portion 34^a which extends between such notches 26 and 30. Said aperture also has a major concentric arcuate edge portion 34^b positioned opposite to said interengaging track portion 34^a and to said locking notches, and I utilize said edge portion 34^b as a stop against excessive linear movement of the plate 17 and a guide-track for a fulcrum or pair of fulcrum members 31 and 32 on the leg plate 17. As shown, the fulcrum members 31 and 32 are positioned on said plate 17 below said locking tongues and are pressed up from the metal of the plate 17 to protrude into said circular aperture above said major arcuate stop and guide edge 34^b of the aperture 33. Said protruded fulcrum members 31 and 32 and the edge track 34^b are relatively positioned in relation to said track 34^b to permit a sufficient linear movement to enable locking and releasing movements of said tongue 24 into the edge notches 26 and 30, while functioning as a limiting stop for said releasing movement so as to prevent disengagement of the plates at the end of a manual notch-releasing movement of the leg and its plate 17. The fulcrum members 31 and 32, when manually pulled down into engagement with said edge portion 34^b, then assume a position in which they will, in conjunction with said edge portion 34^b, guide the leg plate in an arcuate movement from one extreme position to the other and will serve as spaced non-wedging fulcrums during such movement.

The movement of the locking tongue 24 radially of the circular aperture 33 to enter the notches 26 and 30 thus produces a primary locking engagement between the leg plate 17 and the stationary plate 15, and, in the preferred form of my invention, I provide means for producing a secondary locking engagement between the said plates 15 and 17 by providing in the leg plate 17 the raised or struck-up locking tongue 23 adapted to enter and interengage with quadrantally-positioned outer-edge locking notches 25 and 29 aligned radially in the outer edge of the plate 15 with the primary locking notches 26 and 30 and also to interengage with a guiding track portion 31 positioned between and connecting the notches 25 and 29.

The power of the spring 19 is applied to the revolvable leg 18 at a point adjacent to the upper end thereof and the fulcrum members 31, 32 are revolvable with said leg and positioned below the point of application of power. This is accomplished by anchoring the spring 19 on one of the pressed up studs 20 extending a portion thereof across the stationary plate 15 into abutment with a second pressed up stud 20 and then re-entrantly bending the free end to provide an angular operating extension which has a portion engaging an aperture in the leg plate 17.

In the preferred form of my invention, the pair 75

of protruding fulcrum members comprise studs pressed up from the metal of the plate, one of the members of such pair being located on each side of the longitudinal median line of the leg plate and, as aforesaid, below said point of power application.

In operation, the power of the spring is adapted to press or force the leg plate 17 and leg 18 linearly or in a direction parallel to the axis 10 thereof toward the locking notches to cause a locking movement thereof, while a reverse movement manually will cause a release from such notches. Upon such reverse downward manual linear movement of the leg, the protruding studs 15 will engage two points of the major arcuate guiding edge portion of the circular opening or hole 33, and functioning as a non-wedging double fulcrum will, in engagement with said major arcuate guiding edge, enable a facile manual movement of the revolvable leg plate 17 from folded to extended positions and vice versa. While the leg is thus being swung manually from the folded position shown in Fig. 2 to the extended position shown in Figs. 1 and 3 the non-wedging 20 points of contact of the fulcrum members with the said major arcuate guiding track will assume and maintain a triangular relationship to the point of application of power, and viewing the leg as a lever moving about said fulcrum with the 25 power of the spring as the load, an easy movement of the load is assured, and in view of the leverage thus obtained a spring may be employed that is sufficiently strong or powerful to cause a positive, quick and snapping movement of the 30 locking tongues into their respective notches so soon as the alignment therewith is reached.

In assembling my fixture for attachment to the leg and table I preferably first securely fasten the leg plate 17 to a surface of the leg 18 by the 40 screws 35. The plate 15 is then mounted in proper position on the plate 17, the spring is applied and the leg with the parts thus mounted is placed in position over the apron and fastened thereto by the screws 21. Three of these screws 45 may be applied while the leg is in the position shown in Fig. 1 and the other screw may be applied when the leg is turned into the position shown in Fig. 2.

Figs. 7-10 inclusive show an application of my 50 invention to a metallic folding table. The stamped portions 23-24 and protrusions 31-32 are drawn from the metal of the leg itself thereby eliminating completely the use of the leg plate 17. If very thin material is used for the leg, 55 heavier metal clips could be welded on to take the place of the portions 23-24. The pressed up portion 20 would be welded to the apron of the table or fastened in any other suitable way. Plate 15 could also be provided with an angular 60 piece 36, also welded to the apron of the table, and adapted to give reinforcement to the corner of the table. I have also shown a modification of the spring 15. As previously described the 65 spring 15 hooked into the leg plate 17. As shown in Figs. 8-9 the spring 15 is straight at the active end and works against protrusion 37 of the leg.

I claim:

1. In a fixture for a folding leg including a folding leg and a supporting frame, the combination of a pair of plate members of rigid material, one of said plate members being fastened to a surface of the folding leg and the other member being attached to an adjacent surface of the supporting frame, each of said plate members having substantially flat outer surfaces facing

each other and disposed in lapped relationship, one of said plate members being a single stationary base plate fixedly mounted in spaced relationship to the supporting frame surface to provide a restricted space between said stationary plate and said frame surface and to cause the inner plate surface within said restricted space to be positioned above said supporting frame surface, and the other plate member being a single movable plate fastened to and movable with the folding leg, said movable plate being mounted on said base plate to have arcuate and radial sliding movements on the facing surface thereof, said stationary base plate having an aperture positioned interiorly of the plate edges, said aperture having formed in its edge a pair of locking notches arranged in alignment with the longitudinal axis of the folding leg in the folded and extending positions thereof, said aperture also having formed in its edge a track portion disposed between said notches, said movable plate having a protruding locking tongue engageable upon said radial sliding movement of said movable plate with said locking notches and being movable in said arcuate movement along said intermediate track, said locking tongue also having a rim portion extending into said restricted space to engage and slidably move during said arcuate and radial movements in contact with said inner surface of said stationary plate along the edges of said notches and track portion and to serve as an engaging and assembling element for said movable and stationary members, said a spring normally urging said locking tongue in the direction of said notches and intermediate track.

2. A fixture for a folding leg as claimed in claim 1 in which the stationary base plate also has an outer edge provided with secondary locking notches aligned with the locking notches of said interior aperture and said outer edge is provided with an intermediate track connecting said secondary locking notches, and said movable plate has a second locking tongue engageable with opposite surfaces of said stationary plate along said secondary locking notches and their connecting track.

3. In a fixture for a folding leg including a folding leg and a supporting frame, the combination of a pair of plate members of rigid material, one of said plate members being fastened to a surface of the folding leg and the other member being attached to an adjacent surface of the supporting frame, each of said plate members having substantially flat outer surfaces facing each other and disposed in lapped relationship, one of said plate members being a single stationary base plate fixedly mounted in spaced relationship to the supporting frame surface to provide a restricted space between said stationary plate and said frame surface and to cause the inner plate surface within said restricted space to be positioned above said supporting frame surface, and the other plate member being a single movable plate fastened to and movable with the folding leg, said movable plate being mounted on said base plate to have arcuate and radial sliding movements on the facing surface thereof, said stationary base plate having an aperture positioned interiorly of the plate edges, said aperture having formed in its edge a pair of locking notches arranged in alignment with the longitudinal axis of the folding leg in the folded and extended positions thereof, said aperture also having formed in its edge a track portion disposed between said notches, said movable plate having a protruding locking tongue engageable upon said radial sliding movement of said movable plate with said locking notches and being movable in said arcuate movement along said intermediate track, said locking tongue also having a rim portion extending into said restricted

space to engage and slidably move during said arcuate and radial movements in contact with said inner surface of said stationary plate along the edges of said notches and track portion and to serve as an engaging and assembling element for said movable and stationary members, said movable plate also having protruding fulcrum means positioned within said interior aperture to serve as a stop for limiting and preventing excessive radial sliding movement of said movable plate to avoid disengagement of the rim flange portion and also to function as a shifting fulcrum movable along an edge portion of said circular aperture remote from said locking notches to enable a guided movement of said locking tongue from one locking notch to the other, and a spring normally urging said locking tongue in the direction of said notches and intermediate track.

4. A fixture for a folding leg as claimed in claim 3 in which the protruding fulcrum means comprises a pair of protruding fulcrum members, and one of the members of said pair is positioned adjacent to and at one side of the longitudinal median line of said movable plate and the other member is similarly positioned at the opposite side of said median line.

5. In a fixture for a folding leg including a folding leg and a supporting frame, the combination of a pair of plate members of rigid material, one of said plate members being fastened to a surface of the folding leg and the other member being attached to an adjacent surface of the supporting frame, each of said plate members having substantially flat outer surfaces facing each other and disposed in lapped relationship, one of said plate members being a single stationary base plate fixedly mounted in spaced relationship to the supporting frame surface to provide a restricted space between said stationary plate and said frame surface and to cause the inner plate surface within said restricted space to be positioned above said supporting frame surface, and the other plate member being a single movable plate fastened to and movable with the folding leg, said movable plate being mounted on said base plate to have arcuate and radial sliding movements on the facing surface thereof, said stationary base plate having an aperture positioned interiorly of the plate edges, said aperture having formed in its edge a pair of locking notches arranged in alignment with the longitudinal axis of the folding leg in the folded and extended positions thereof, said aperture also having formed in its edge a track portion disposed between said notches, said movable plate having a protruding locking tongue engageable upon said radial sliding movement of said movable plate with said locking notches and being movable in said arcuate movement along said intermediate track, said locking tongue also having a rim portion extending into said restricted space to engage and slidably move during said arcuate and radial movements in contact with said inner surface of said stationary plate along the edges of said notches and track portion and to serve as an engaging and assembling element for said movable and stationary members, said

stationary base plate having protrusions on its frame-facing surface to provide said restricted space between said plate and said stationary frame surface, and a spring anchored and confined within said restricted space and engaging said movable member to cause said tongue to be moved in the direction of said locking notches and intermediate track.

6. In a fixture for a folding leg including a folding leg and a supporting frame, the combination of a pair of plate members of rigid material, one of said plate members being fastened to a surface of the folding leg and the other member being attached to an adjacent surface of the supporting frame, each of said plate members having substantially flat outer surfaces facing each other and disposed in lapped relationship, one of said plate members being a single stationary base plate fixedly mounted in spaced relationship to the supporting frame surface to provide a restricted space between said stationary plate and said frame surface and to cause the inner plate surface within said restricted space to be positioned above said supporting frame surface, and the other plate member being a single movable plate fastened to and movable with the folding leg, said movable plate being mounted on said base plate to have arcuate and radial sliding movements on the facing surface thereof, said stationary base plate having an aperture positioned interiorly of the plate edges, said aperture having formed in its edge a pair of locking notches arranged in alignment with the longitudinal axis of the folding leg in the folded and extended positions thereof, said aperture also having formed in its edge a track portion disposed between said notches, said movable plate having a protruding locking tongue engageable upon said radial sliding movement of said movable plate with said locking notches and being movable in said arcuate movement along said intermediate track, said locking tongue also having a rim por-

tion extending into said restricted space to engage and slidably move during said arcuate and radial movements in contact with said inner surface of said stationary plate along the edges of said notches and track portion and to serve as an engaging and assembling element for said movable and stationary members, said stationary plate also having an outer edge provided with secondary locking notches aligned with the locking notches of said interior aperture and having an intermediate connecting track, and said movable plate having a second locking tongue engageable with opposite sides of said stationary plate along said secondary locking notches and their connecting track, said movable plate also having a pair of protruding-fulcrums positioned within said interior aperture to serve as stops for limiting and preventing excessive radial sliding movement of said movable plate and to avoid disengagement of the rim flange portion and so to function as shifting fulcrums movable along an edge portion of said circular aperture remote from said locking notches to enable a guided movement of said locking tongue from one locking notch to the other, and a spring mounted on said stationary plate and engaging said movable plate to normally urge said locking tongue in the direction of said notches and intermediate tracks.
